RAILWAY TRUCK

Harry M. Pflager, St. Louis, Mo., and Edmund S. Beckette, East St. Louis, Ill., assignors to General Steel Castings Corporation, Granite City, Ill., a corporation of Delaware

Application August 12, 1935, Serial No. 35,710

14 Claims. (Cl. 105—190)

This invention relates to railway rolling stock and consists in novel truck structure.

The main object of the invention is to provide a light weight truck particularly adapted for high speed service.

Another object is to dissipate minor lateral shocks applied to the truck frame when the wheels strike rail joints, switches, and other irregularities in the track producing jiggling of the frame.

Another object is to support the bolster hangers from the truck frame by rubber members and, preferably, to arrange the members so that their resiliency is not limited to merely resisting compression forces.

A copending application, Serial No. 17,415, filed April 20, 1935, by one of the present inventors illustrates a light weight truck for high speed service in which three sets of springs are provided to produce easy riding qualities, namely, those carried from the journal boxes and directly supporting the truck frame, those seated on the frame transoms and pivotally supporting the bolsters, and those between the hangers and the bolster. The sets of springs have different characteristics so as to have a mutually dampening effect.

In the present invention, the springs directly supporting the bolster hangers are replaced by rubber resilient members which provide new and useful means for resiliently supporting the swing hangers.

In the accompanying drawings illustrating the invention—

Figure 1 is a partial top view of a truck embodying the invention.

Figure 2 is a partial side view of the structure in Figure 1.

Figure 3 is a vertical transverse section on the line 3—3 of Figure 1.

Figure 4 is a half vertical longitudinal section and side view taken substantially on the line 4—4 of Figure 1 but showing an end portion of the truck.

Figure 5 is a detail horizontal section taken on the line 5—5 of Figure 3.

Figure 6 is a detail vertical longitudinal section taken on the line 6—6 of Figure 1.

Figure 7 is a view similar to Figure 6 but showing a modification.

Figure 8 is a partial top view of a truck embodying a modification.

Figure 9 is a detail vertical longitudinal section taken on line 9—9 of Figure 8.

Figure 10 is a vertical transverse section taken on line 10—10 of Figure 9.

Figures 1 to 6 show a truck including a pair of wheeled axles 1, journal boxes 2 and equalizers 3 mounted on the boxes and supporting the truck framing by means of coiled springs 4. The truck frame comprises side members or wheel pieces 5 and box section transoms 6. Brake hanger brackets 7 and 8 are provided at the ends of the side members and at the intersections of these members with the transoms.

Each end of each transom is recessed to form an enclosure which houses two pairs of rubber members 15. Each member 15 is vulcanized to plates 16 on the opposite sides thereof. Shoulders 24 on the transom side walls 14 seat the rubber members. A yoke or hanger support includes elongated vertical ribs 18 extending over the two pairs of rubber members 15, horizontal webs 35 between the corresponding ends of ribs 18 and overlying the rubber members, and depending vertical webs 17 each inserted between a corresponding pair of rubber members 15.

A pin 19 seated in ribs 18 pivotally mounts a swing hanger 10 depending between members 15 and through an opening 20 in the bottom of the transom. Lugs 21 projecting from one of ribs 18 mount a bolt 22 securing pin 19 in position. Hanger 10 at its lower extremity has a slot 23 receiving the end of a bar 11 supporting elliptic springs 12 on which the bolster 9 is carried.

The sides of webs 17 converge downwardly as do the abutting inner plates 16 on the rubber members. The lower faces of these members are inclined upwardly and toward each other to provide for downward deflection of the rubber, when the load is applied, without excessive amounts of rubber projecting below the level of the lower edge of the outer plates 16. Shims 36 are provided between the horizontal webs 35 and the upper, inner edges of the rubber members or the upper edges of the inner plates 16.

In assembling these parts, downward pressure on the hanger produces a wedging action between webs 17 of the hanger yoke and the abutting inner plates 16 on the rubber members, and the webs slide downwardly relative to the inner plates of the rubber and apply horizontal compressive force on the rubber until the shim engages the upper inner edges of the inner plates 16.

It is a characteristic of rubber that if it is put under compression it will have less deflection under a given load and thereby offer greater resistance to other forces applied thereto. The

shims are used to adjust the component of compression so as to provide proper deflection.

If the resiliency and other qualities of the rubber is lessened, due to constant use or other reasons, the proper resistance to the vertical and transverse displacement of the hanger may be obtained by removing one or more shims so as to permit the wedge webs 17 to slide downwardly further relative to the inner plates 16 of the 10 rubber member to increase the horizontal compressive force on the rubber. As this force is increased, less deflection results, but the rubber offers greater resistance to other forces than before removal of the shim or shims.

15 The rubber hanger mountings carry the vertical forces, due to the loads on the truck, and resist the transverse forces which are applied to the truck. These forces subject the rubber members to shearing, bending, and twisting forces, resulting in freer action of the rubber than would be the case if the members were mounted on a horizontal member of the transom with the hanger top bearing member or the hanger itself supported on top of the members, thus subjecting 20 the members principally to compression forces only.

Figure 7 shows a web 26 of a hanger yoke similar to that in the previous form but the sides of web 26 and the abutting inner plates 27 on the rubber 30 members 28 are disposed vertically. Shims 39 are provided between the portions 26 of the yoke and the inner plates of the rubber members 28 to adjust the component of compression on the rubber members. To facilitate assembly of the yoke 35 between the rubber members, the lower portion of the yoke web is beveled at 40. Shims 38 are provided between the shoulder on the bearing member and the upper edges of the inner plates so as to adjust the height of the swing hanger in 40 the truck.

In Figures 8 to 10, each bolster hanger 29 is supported directly by the rubber members 30 without the interposed bearing device of the previous forms. Hanger 29 has a downwardly 45 tapered upper portion 31 against the sides of which abut the similarly tapered inner plates 32 on members 30. The rubber members are positioned between shoulders 33 on the transom side walls, and shoulders 34 at the upper end of the hanger overlap the upper edges of the rubber 50 members. Fillers or shims 35 provide for adjusting the component of compression on the rubber members in the same manner as the shims in Figures 1 to 6. In this form the rubber 55 members are twisted by swinging of the bolster hangers, the members yielding under the torsional forces applied through the hangers.

The rubber members function to carry the vertical load on the truck, to absorb the lateral 60 shocks due to the jiggling of the truck frame when the wheels strike rail joints, switches, etc., and to tend to dampen the effect of the bolster springs 12 and frame supporting springs 4 so that the truck rides smoothly and evenly. In 65 Figures 8 to 10, the rubber members have a third function, to twist and offer approximately the same lateral resistance as that obtained by the usual inclined swing hanger. In all forms, the 70 bolster is effectively centered due to the resistance to swinging which gradually increases as the bolster is displaced from its center position.

The invention is not limited to the details shown but may be modified as will occur to those skilled 75 in the art and the exclusive use of all those modi-

fications coming within the scope of the claims is contemplated.

What is claimed is:

1. In a railway truck, framing, rubber members thereon, elements between said members, 5 said members being compressed horizontally between said framing and said elements to support the latter, hangers carried by said elements, and a bolster carried by said hangers.

2. Structure as specified in claim 1 in which 10 said hangers are pivoted on said elements.

3. In a railway truck, framing having upright opposing elements, individual rubber members independently mounted on said elements and having substantially parallel opposing faces, and a 15 bolster support device between and compressing said rubber members and yieldingly carried thereby, said support device having downwardly converging parts engaging opposing faces of said rubber members for adjusting the compression of 20 said rubber members.

4. In a railway truck, framing with opposed substantially parallel walls, rubber members mounted on said walls, and a bolster supporting device carried by said members and including 25 a portion between parts of said members spaced from said walls and compressing them laterally against said walls, such compression increasing with the load on said device, said device being movable horizontally by distortion of said members. 30

5. In a railway truck, spaced transverse frame elements, rubber members at the opposite ends of said elements, said members being arranged in pairs, support devices between and compressing 35 the members of each pair horizontally, hangers pivotally suspended on said devices, and a bolster carried by said hangers.

6. In a railway truck, spaced pairs of rubber members, a device having spaced elements gripped 40 between opposing faces of each pair of said members, and a bolster hanger pivotally carried by said device and swinging between said elements and between said pairs of members.

7. In a railway truck, opposing parts with 45 shoulders spaced vertically and horizontally from each other, rubber members mounted on said parts with outer portions engaged by said shoulders, and bolster swing hanger structure carried by the inner portions of said rubber members, 50 said shoulders functioning to hold said rubber members against movement horizontally or vertically by said hanger.

8. In a railway truck, a frame member having a recessed portion, separated rubber members housed 55 therein and mounted on opposite walls of said portion, and a bolster hanger between said members and depending through said frame member.

9. In a railway truck, horizontally opposing parts, separated members mounted on said parts and extending therefrom towards each other, a device supported by said members, and a bolster hanger element carried by said device between the inner portions of said members, said members 60 being compressed between said parts and said device and the compression on said members being increased with the load on said element. 65

10. In a railway truck, opposing parts, rubber members mounted on said parts, and a bolster 70 hanger secured between and suspended from said members, said members being torsionally resilient to accommodate swinging of said hanger.

11. Structure as specified in claim 10 including filler means between said members and said

hanger element for adjusting the compression of said rubber members.

12. Structure as specified in claim 10 including filler means between said rubber members and said hanger for adjusting the component of compression on the rubber members to vary the resistance of the rubber members to deflection, shearing, bending, or torsional forces.

13. In a railway truck, a frame having upright walls spaced apart, rubber members independently mounted on said walls and extending towards each other, a device gripped between said rubber members, a bolster swing hanger pivoted

on said device, said hanger being yieldingly supported on said frame by the flexing of said rubber members.

14. In a railway truck, a frame, spaced rubber members seated on said frame at each side of the truck, devices at each side of the truck each extending between and carried by adjacent rubber members and movable transversely of the truck by the yielding of said members, swing hangers carried by said devices, and a bolster carried by said swing hangers.
